(57) **CLAIM**

The ornamental design for a bracelet, as shown and described.

DESCRIPTION

1. Bracelet

1.1 : Perspective

1.2 : Front

1.3 : Back

1.4 : Right

1.5 : Left

1.6 : Top

1.7 : Bottom

1.8 : Open bracelet perspective

1.9 : Open bracelet perspective

The bracelet comprises a flexible band, with a buckle connected to one end, which, on the front, has an H-shaped pattern and which on the inside defines a passage where the other end of the band, folded on itself, is held.

1 Claim, 9 Drawing Sheets
